UNITED STATES PATENT OFFICE.

ALBERT HENKELS, OF LANGERFELD, NEAR BARMEN, GERMANY.

LACE.

1,187,621.

Specification of Letters Patent. Patented June 20, 1916.

Application filed July 2, 1913. Serial No. 777,105.

To all whom it may concern:

Be it known that I, ALBERT HENKELS, a citizen of the German Empire, residing at Langerfeld, near Barmen, in the Province 5 Westphalia, Germany, have invented certain new and useful Improvements in Laces, of which the following is a specification.

In machine-made plaited work the threads necessarily all run more or less in a diagonal direction and consequently impart to the 10 article its characteristic plaited appearance. Attempts have already been made to produce, on braiding machines having one bobbin to each plate, lace resembling gauze by connecting together at regular intervals pairs of 15 plaiting threads arranged at a definite distance apart and running longitudinally, such connection being effected by means of a special pair of bobbin threads passing like 20 the weft of a woven fabric to and fro across the entire width of the plaited fabric. Since in such a process, however, the pair of bobbins which imitate the weft must pass to and fro always across the entire width of the 25 fabric and all the other bobbins remain inoperative, while said bobbins are passing to and fro, it follows that this method of working must take up an extraordinary amount of time and must consequently be expensive. 30 There is moreover the disadvantage that it is impossible to produce patterns in or upon such a plaited fabric.

Now this invention is a new pillow lace with a gauze-like foundation made on a 35 bobbin-machine in which all the defects above referred to are obviated, by the bobbin threads being plaited in groups to form narrow strips running in the longitudinal direction and forming the warps and by these strips 40 then being connected together at intervals for the purpose of forming the weft by the simultaneous interchange of the marginal threads of adjacent plaited strips. By the manner of arranging the threads adopted 45 the separate longitudinal strips are connected together in the direction of the weft across the entire width of the plaited fabric with the result that the time required and the expense involved are considerably reduced in comparison with the method heretofore usual, while the further advantage is 50 at the same time realized that by the constant interchange of the marginal threads of two adjacent strips of plaited fabric there 55 can be secured a compact combination thereof along a considerable length with the re-

sult that the squares produced in the foundation pattern can by this means, independently of each other, be made either open or closed as may be desired. By a suitable arrangement of these open or closed squares there can be produced simultaneously with the manufacture of the gauze-like foundation and on the latter, certain flat patterns formed of closed squares.

The accompanying drawings illustrate lace made in accordance with this invention: wherein—

Figure 1 shows the pattern of the lace diagrammatically, Fig. 2 shows a small portion thereof on an enlarged scale and Fig. 3 a portion where the plaited threads cross each other, the threads being shown somewhat loose to enable the position of the threads to be clearly seen.

In the example illustrated the lace fabric consists of the separate plaited strips *a* which are intended to correspond to the warp thread of ordinary gauze material and run at uniform distances apart parallel 80 to the longitudinal direction of the entire plait, and each of which as is clearly shown in Figs. 2 and 3, is composed of four threads. At regular intervals the plaited strips *a* are connected with each other by the interchange of the marginal threads of two adjacent strips, these threads forming a transverse piece *b* that lies at right angles to the strips *a* and corresponds to the weft of the gauze. The squares *c* formed by the individual longitudinal and transverse strips may be either open or, as indicated at *d*, closed by the continuous interchange of the two marginal threads of adjacent plaited strips. As each of the separate squares may 90 be either open or closed as desired, independently of any of the others, there can be produced by suitably grouping the open and closed squares, quite irregular flat patterns of any desired outline on a gauze 100 foundation as shown in Fig. 1 similar to those produced on ordinary gauze by figuring. The separate squares may be more or less closely filled as desired, a certain amount of shading being capable by this means of 105 being introduced into the pattern. Preferably two of the four threads of the separate warp strips are somewhat thicker than the others, these thicker threads being used for the formation of the weft while the thinner threads extend through the entire 110 length of the warp strip. By this means the

apparent thickness of the weft and the warp are caused to differ only to an inconsiderable and scarcely noticeable extent.

What I claim as my invention and desire 5 to secure by Letters Patent is:—

As an article of manufacture, lace having a ground work of squares, some of which are left open whereas others are filled in the lacemaking operation so as to produce any 10 desired solid pattern on an openwork ground, the borders of the squares being formed by pairs of threads twisted about each other and running laterally and by longitudinally running groups of four

plaited threads, each of said groups consisting of two larger and two smaller threads and the two threads first mentioned being drawn from the borders of said four thread groups, the threads for filling the closed squares being similarly supplied.

In testimony whereof I have signed my name to this specification in the presence of 20 two subscribing witnesses.

ALBERT HENKELS. [L.S.]
